SIDNEY W. WINSLOW, OF ORLEANS, MASSACHUSETTS, ASSIGNOR TO UNITED SHOE MACHINERY COMPANY, OF PATERSON, NEW JERSEY, A CORPORATION OF NEW JERSEY.

TOP LIFT.

1,078,652.

Specification of Letters Patent. Patented Nov. 18, 1913.

Application filed November 15, 1912. Serial No. 731,550.

To all whom it may concern:

Be it known that I, SIDNEY W. WINSLOW, a citizen of the United States, residing at Orleans, in the county of Barnstable and 5 State of Massachusetts, have invented certain Improvements in Top Lifts, of which the following description, in connection with the accompanying drawings, is a specification, like reference characters on the drawings indicating like parts in the several figures.

In the use of top lifts, whether compressed or uncompressed, considerable difficulty is caused by displacement of the leather in the 15 driving of the short nails or "slugs" which are inserted in the marginal portion of the top lift close to the edge and outside the heel attaching nails. In the first place the stock immediately surrounding the slug on 20 the grain side bulges somewhat as the slug is driven. Again, in driving the slug the stock is to some extent forced ahead of it and, as the point of the slug emerges on the flesh side of the top lift, a considerable 25 amount of stock is pushed out so that each slug is surrounded on the flesh side by a portion of the stock which is raised above the plane of the flesh side. The stock contained in these bulges, which is hardened 30 by the pressure of the slug as it is driven, tends to force, and frequently does force, the top lift away from the outer lift of the heel to which the top lift is attached, resulting in "checking" on the edge of the heel 35 at the line of junction of the top lift and the heel. This tendency to check is aggravated when the slugs are blunt ended or when they are so short that they protrude only slightly beyond the flesh surface 40 of the top lift. Some manufacturers prefer to use blunt ended slugs and it is desirable for obvious reasons of economy that the slugs be as short as preferable.

An important object of this invention is 45 to obviate the disadvantages which have resulted from the displacement of stock in the slug driving operation and to this end a feature of the invention is a top lift provided on its flesh side with a recess or 50 cesse, preferably in the form of a continuous groove, substantially in the line in which the slugs are to be driven. When the slugs are driven the material forced out on 55 the flesh side finds lodgment in this groove and will not be forced beyond the plane of

the flesh side. At the same time the relief which is afforded by this groove prevents much of the displacement which would otherwise take place, as above explained, on the grain side. The groove will preferably 60 terminate a short distance from the breast of the top lift on each side to provide for removal of stock in the breasting operation without exposing the ends of the groove to view on the breast of the heel. While this 65 feature of the invention may be incorporated in any top lift, I prefer to compress the top lift in the same operation in which the groove is formed and thereby impart to the top lift the great advantages of compression as well as the advantages secured 70 by the groove. An important advantage of forming the groove in a compressed or condensed top lift is that the marginal portion of the top lift is thereby rendered much 75 denser than the interior portion. As is well known, the portion of the top lift which wears off first is the marginal portion of the grain face around the curved rear end of the top lift and it is highly advantageous 80 that this should be the hardest and firmest portion of the top lift.

It has heretofore been the practice to concave the top lift spanking plate on the healing machine for the purpose of crowding 85 down and rounding somewhat the margin of the top lift as it is spanked on the heel. The reason for this is that after slugs have been inserted in a flat top lift the lift is usually higher around its margin than in 90 the interior, owing to the displacement of the stock in the slug driving operation. The practice of concaving the spanking plate has been unsatisfactory, as the concavity in a spanking plate so formed and 95 adapted for top lifts of medium size would be too small for large top lifts and too large for small top lifts.

Another object of this invention is to 100 remedy this difficulty by an improvement in the top lift, and accordingly a feature of the invention is a compressed top lift having formed on its grain face a narrow slug receiving margin which is beveled toward the edge. Preferably this margin will be of 105 such width that the line in which the slugs are driven will be approximately along the middle of the margin and the bevel will be at such an angle that the bulging stock forced upwardly during the slug driving 110

operation will not be raised above the inner edge of the bevel. This beveled margin has a further advantage when the top lift is formed with an interior ornamented area 5 depressed below the normal plane of the margin. It occasionally happens that top lifts of this character as heretofore used have their marginal portions crowded down somewhat in the top lift spanking operation so that the plane of the margin is then offset only slightly, if at all, from the ornamented area. When the slugs are driven into such a top lift provided with a margin having a substantial bevel the margin still 10 has some bevel after the slugs have been inserted, so that the margin can be buffed by a buffing roll operating in a plane at a slight angle to the general plane of the grain face without danger of defacing the 15 interior ornamented area.

A top lift having an interior ornamented area formed by pressure and surrounded by a marginal slug receiving area offset from or extending above the plane of the interior 20 ornamented area is of commercial advantage because the ornamented area gives an attractive appearance to the top lift and further because superficial defects in stock, otherwise suitable for top lifts, are hidden 25 or covered up by the ornamented area, while the margin and the heads of the slugs may be buffed without defacing the ornamentation. Such top lifts, however, whether compressed or uncompressed, have the disadvantage 30 that the marginal portion surrounding the ornamented area is distinctly less dense than the interior ornamented area, while as above explained, the greatest wear on the top lift is on the curved marginal 35 portion at the rear.

With the object of remedying this disadvantage another important feature of my invention is a top lift having an interior ornamented area surrounded by a marginal 40 portion offset outwardly above the plane of the interior portion, with the attendant well known advantages, in which the marginal portion is as dense as or preferably substantially denser than the interior portion.

Various other features and advantages of the invention will appear more fully in the following detailed description when read in connection with the accompanying drawings.

In the drawings: Figure 1 is a perspective view, partly in section, of one form of top lift embodying the present invention, the section being taken in the plane 1—1 of Fig. 2; Fig. 2 is a perspective view of the flesh side of the top lift shown in Fig. 1; Fig. 3 is 55 a transverse sectional view of an ordinary top lift which has been slugged; and Fig. 4 is a transverse sectional view of the top lift shown in Fig. 1 after it has been slugged.

Referring to the drawings, 2 indicates a 60 top lift of any usual form which may be

either compressed or uncompressed. It is customary to drive slugs 4, 4, Fig. 3, into or through the top lift along the margin after the top lift has been attached to a heel. In the operation of driving these slugs the 70 stock is crowded out somewhat on the grain side of the lift, forming bulges 6 around the heads of the slugs. The stock is also forced toward and outwardly from the face of the flesh side of the lift by the points of the 75 slugs, forming hardened bulging portions 8 upon the flesh side where the points of the slugs emerge.

The bulging at the points 8 on the flesh side of the lift has heretofore caused a great deal of trouble because the stock crowded ahead and compressed by the slugs is constantly tending to force the lift away from the heel, opening a crack or "check" between the lift and the heel. This is particularly noticeable when blunt ended slugs or short slugs which protrude little, if any, beyond the flesh side of the lift are used. I have found that the difficulties resulting from the displacement of the stock in the 90 slug driving operation are effectively overcome by forming in the flesh side of the lift a recess in which the excess stock may find lodgment. Preferably, the recess is in the form of a U-shaped groove 14 terminating 95 at points 20, 20, a sufficient distance from the breast edge 22 of the lift to allow some stock to be removed in the heel breasting operation. While these advantages may be obtained by a groove of any desired cross 100 section suitable to receive and afford relief for the stock displaced by the slugs, the form illustrated in the drawings, in which the groove is shown as decreasing gradually in depth from an outer shoulder 15 toward 105 the interior portion of the lift, has the advantage that the largest possible area is presented for firm engagement with the heads of the heel attaching nails upon which the top lift is spanked and which are chiefly depended upon to secure the top lift to the heel, and I consider this the best form. In order to afford relief for the stock displaced by the slugs the groove should be in line with the slugs or near enough to such a line 110 to permit the displaced stock to find lodgment in the groove. While the main function of the groove 14 is to receive the bulges 115 I have also found that the relief which it affords prevents the stock from being raised 120 around the heads of the slugs as much as would occur otherwise. For this reason considerably less buffing is required to bring the heads of the slugs and the margin down to a uniform level surface, with the consequent saving of the valuable grain portion 125 of the leather and of buffing material and labor.

While the groove just described is of advantage in any top lift, it has an additional 130

advantage in a compressed top lift because when the groove is formed during the compressing operation a much greater pressure is imparted to the marginal portion of the top lift than to the interior, thus making the marginal portion, which receives the greatest wear, much the hardest and firmest part of the lift. Furthermore, I have found that a top lift having an interior ornamented area with a marginal slug receiving area offset above the ornamented area, may be greatly improved by the embodiment in it of this feature of my invention. Top lifts have heretofore been formed with an interior ornamented area and an offset marginal slug receiving portion and such top lifts have been extensively used both on account of their attractive appearance and because superficial defects or blemishes in the leather are hidden by the ornamentation. A further advantage of such a top lift is that the heads of the slugs and the bulging stock surrounding them can be buffed off by an ordinary buffing roll without defacing the interior ornamentation, but it has had the disadvantage that the marginal portion was substantially less dense, and therefore less durable, than the interior portion, although of course the marginal portion, particularly around the curved rear end, receives most of the wear to which the top lift is subjected. An important feature of my invention is a top lift of this type having a marginal portion which is at least as dense as, and is preferably distinctly denser than, the ornamented interior. The greater density is imparted to the marginal portion by a die which forms the groove on the flesh side and this groove will preferably be formed at the same time that the ornamented area is produced on the grain side.

An objectionable result of the bulging of the stock during the slug driving operation on a flat top lift, whether compressed or un-compressed, is that the grain face of the top lift is made somewhat concave, as shown in Fig. 3. This makes it impossible to buff the interior portion of the grain face of the lift with an ordinary buffing roll, which is cylindrical, without buffing the margin so deeply as to cut through the grain of the leather. It is exceedingly undesirable to do this because the grain is the best part of the leather and should be preserved around the margin of the lift where the lift receives the most wear. Unsatisfactory attempts to overcome this difficulty have been made by forming the top lift spanking plate of the heel attaching machine with a cavity in its face shaped to round slightly the margin of the top lift as it was spanked on the heel. This expedient has been unsatisfactory because the concave face of a spanking plate would be of the right shape for only one size of top lift. I have over

come this difficulty by an improvement in the top lift. To this end one feature of my invention consists in forming upon the grain side of the top lift a beveled margin 10 similar in form to that shown in Figs. 1 and 2. The essential characteristics of this feature of the invention are that the bevel 10 be formed along the slugging line and be at least a little wider than the row of slugs.

When a top lift having a beveled margin such as is shown in Figs. 1 and 2 is slugged, the grain surface is bulged somewhat around the slugs, as in the case of the ordinary top lift, but sufficient bevel is provided so that after the slugs are driven the edge of the lift will be no higher than the inner edge of the beveled margin. This may be seen clearly by referring to Fig. 4 wherein the margin 10 has been bulged somewhat by the slugs, but not enough to raise the edge of the lift above the inner edge of the margin. When a top lift having a plain grain surface embodying this feature of the invention is slugged the lift will usually not be concaved, as in Fig. 3, and the interior portion of the surface may be buffed without removing the grain at the edge. I prefer, however, to form top lifts with both the beveled margin on the grain side and the groove on the flesh side in order to insure that this difficulty shall be entirely overcome as well as to secure all the other advantages which may be obtained by combining these features. This beveled margin has particular utility in a top lift having an interior ornamented area surrounded by an offset slug receiving portion. It often happens that the margin of such a top lift is crowded down somewhat in the top lift spanking operation so that its surface is only slightly, if at all, above the ornamented area. When the slugs are inserted the outer edge of the margin is raised so that the margin is inclined inwardly toward the ornamented area and it is difficult or impossible to buff it without defacing the ornamented area. This drawback is overcome according to my invention by forming the bevel 10 at a sufficient angle so that after the top lift is slugged the margin will still have a slight outward bevel. The margin may then be buffed down to such a surface as that indicated by the broken line 16 in Fig. 4 with an ordinary roll without danger of touching the interior area 12 and without cutting through the grain part of the margin. Furthermore, a top lift embodying this feature of my invention may be provided with an interior ornamented area which is not depressed below the plane of the inner edge of the margin, as the beveled margin may be buffed without danger of defacing the ornamentation.

The beveled margin 10 and the recess or

groove 14 may be produced in various ways but I prefer to mold them by heavy pressure imparted by suitable dies in a powerful compressing machine. So forming them has the advantage that the marginal portion of the top lift may be hardened, and if desired the top lift as a whole may be condensed, at the same operation. By forming the dies properly the ornamentation 12 may be impressed in the grain face of the lift at the same time. Dies adapted for these purposes by suitable changes in the formation of the pressure exerting faces are shown in United States Letters Patent No. 15 772,840, granted Oct. 18, 1904. Such dies may be mounted in a machine of the type shown in United States Letters Patent No. 776,787, granted Dec. 6, 1904.

While the invention has been specifically 20 described with particular reference to a compressed top lift having an interior ornamented area on its grain face, it should be understood that both the beveled margin and the recess or groove in the flesh side of 25 the lift may be used advantageously in a top lift having a flat or smooth grain face and which may be either compressed or uncompressed; and that the marginal portion of relatively great density may also be effectively used in a top lift having a flat face or one which is otherwise uncompressed. Such variations are contemplated as within 30 the spirit and scope of the invention and the claims should be construed accordingly.

35 Having described my invention, what I claim as new and desire to secure by Letters Patent of the United States is:

1. As a new article of manufacture, a top lift adapted for attachment to heels of 40 boots or shoes having a recess in its heel contacting face substantially in the slugging line and of less depth than the thickness of the top lift, to receive stock displaced in the slugging operation.
- 45 2. As a new article of manufacture, a top lift for heels of boots or shoes having a groove in its inner or flesh side so formed and located as to afford relief for the stock displaced during the slugging operation.
- 50 3. As a new article of manufacture, a top lift for heels of boots or shoes having in its flesh side a U-shaped groove located substantially in the slugging line to receive

stock displaced by slugs, the groove terminating at a substantial distance from the 55 breast edge of the lift.

4. As a new article of manufacture, a top lift for heels of boots or shoes having a U-shaped beveled margin on its grain side and a corresponding U-shaped groove in its flesh 60 side.

5. As a new article of manufacture, a top lift for heels of boots or shoes having a slug receiving margin beveled on the grain side and provided in the flesh side with a recess 65 to receive stock displaced by the slugs.

6. As a new article of manufacture, a top lift for heels of boots or shoes having the margin of its outer face beveled toward the edge of the lift, the inner boundary of said 70 beveled portion being within the slugging line.

7. As a new article of manufacture, a top lift for heels of boots or shoes having an ornamented interior portion surrounded by 75 a U-shaped margin beveled on the outer face of the lift toward the edge of the lift, the inner boundary of said beveled portion being within the slugging line.

8. As a new article of manufacture, a top 80 lift having an interior area ornamented by pressure and a U-shaped marginal area offset outwardly above the interior area, the margin being of greater density than the interior portion. 85

9. As a new article of manufacture, a top lift having a compressed ornamented interior area surrounded by a compressed marginal area offset outwardly above the ornamented interior area, the density of the 90 marginal portion of the lift being at least as great as that of its interior portion.

10. A top lift for heels of boots or shoes provided with a groove in the marginal portion of its flesh side, said groove having its 95 minimum depth at its inner edge to afford a maximum interior area for secure engagement with the heads of the heel attaching nails in the spanking operation.

In testimony whereof I have signed my 100 name to this specification in the presence of two subscribing witnesses.

SIDNEY W. WINSLOW.
